Design No. 525

ABBOOTT & LAWRENCE Assignees of SAMUEL H SAILOR.

Design for Gas Oven Plate.

Patented November 9, 1852.

Des. 525

Samuel H. Sailor of Philadelphia, Pa.

Assignor to

James G. Abbott & Archiles Lawrence of same place
Letters Patent No. 525 Dated Nov. 9th 1852

The schedule referred to in these Letters Patent and making part of the same

To all whom it may concern:

Be it known that I, Samuel H. Sailor, of Philadelphia, in the County of Philadelphia, and State of Pennsylvania, have invented or produced new and original designs in "Gas oven plates", and I do hereby

declare that the following is a full, clear, and exact description of the same; reference being had to the annexed drawings, making part of this specification, in which

Figure 1. is an elevation of the oven doors and surrounding frame, exhibiting the entire appearance of the left hand door, and the lettering on the right hand one, but only the outlines of the ornamental portions, which are the same as in the left hand door. Something over one half of the frame or ornaments are shown entire, around the left hand door, but around the right only the outlines are given, the design being the same as seen on the left.

Figure 2. is an elevation of the feed door, cleaning door, ash hole door, and the frame; the whole being shown with the exception of the right hand design on the frame, similar to that on the left.

XX. figure 1. gives the right and curved lines, as viewed in section of the various mouldings, between X. X.

Similar letters refer to the same parts in all of the figures.

The panels of the oven doors A, are sunken, and are formed by the mouldings (a, a); in their centres are the curved tablets (b, b), supported at their corners by the scrolls (d, d) entwined with the palm branches (c, c). Upon the faces of these tablets are the richly embossed shields (e) as seen in the drawing.

In the plain parts of the panels, above and below the curved tablets, is the inscription

"Abbott & Lawrence

Philadelphia Patented 1852." in raised capitals & numerals, arranged as seen in figure 1. —

Upon the bottom of the frame is the ribbed moulding (f), broken as seen in the drawing at (f' f'); and upon the sides are the corbels (x, x), supporting the ribbed semi pillars (f", f") similar to the moulding (f). Upon each of the semi pillars (f"), is the semi torus (g) connecting them with the sweeps (h) as seen in the drawing. These sweeps continue around the top of the frame, and meeting at (k) form a ribbed moulding similar to the moulding

(Upon the bottom of the frame, as seen in figure 1.)

The upper corners and top of the frame is ornamented by foliage arranged as seen in the figure at (b). Upon the plain portion of the top of the frame, and under the centre of the moulding (K) is the inscription "No. 1".

The panel of the clearing door, is sunken, and formed by the mouldings (m); it has in its centre an embossed shield (m') similar to those upon the oven doors. Upon the plain portion of the panel is the inscription

"Abbott & Lawrence

Patented 1852" in raised capitals & numerals, arranged as seen in the drawing.

The panel of the ash hole door is formed by the mouldings (n), and is ornamented with foliage and flowers arranged as represented in figure 2.

The panel of the feeding door is formed by the moulding (p), and is also ornamented with foliage and flowers (p), arranged in a manner similar to those on the ash hole door.

The sides and top of the frame (A) have on their outer edges the mouldings (q), and upon the sides of the frame are the semi-pillars (r. r.) constructed and arranged as set forth in figure 2.

What I claim as my invention or production, and desire to secure by Letters Patent, is the ornamental design of the oven doors (A), the clearing door (C), the feeding door (D), the ash hole door (E), and the configuration & arrangement of the mouldings and ornaments of the frames, (B) and (F), as set forth & described in this specification and the annexed drawings.

In testimony whereof, I have hereunto subscribed my name before two subscribing witnesses.
